ATTORNEY

UNITED STATES PATENT OFFICE.

BENNETT KINDBLADE, OF BATAVIA, ILLINOIS.

ROLLER-SKATE.

SPECIFICATION forming part of Letters Patent No. 329,913, dated November 10, 1885.

Application filed October 11, 1884. Serial No. 145,298. (Model.)

To all whom it may concern:

Be it known that I, BENNETT KINDBLADE, a citizen of the United States, and a resident of Batavia, in the county of Kane and State 5 of Illinois, have invented new and useful Improvements in Roller-Skates, of which the following is a specification, reference being had to the accompanying drawings, illustrating the invention, in which—

10 Figure 1 is a sectional elevation of a roller-skate embodying my improvement; Fig. 2, an inverted view of the skate with one truck removed; Fig. 3, a top view of Fig. 2; Fig. 4, a top view of one of the trucks removed from 15 the boot-support; Fig. 5, a perspective view of the pivot-plate, on which the track is centered, removed.

The nature of the present invention consists in the novel means for adjusting the boot-plate 20 to fit different-sized boots, novel construction and adaptation of double springs to prevent lost motion in the movement of the truck, and the novel construction of truck-hangers, whereby the wear of the connections is on 25 pivots which relieve the peripheries of the attaching-screws from wear, as the whole is hereinafter fully described and shown.

K K' represent the two-part boot-plate of the skate, K' being the heel. D D represent 30 brackets attached, respectively, to the under sides of the plates K K' by means of rivets in a substantial manner. Tapped through these brackets is a right-and-left screw-rod, O, to which is affixed a burr, P, for turning the screw-rod so as to bring the brackets to or 35 from each other and shorten or lengthen the two-part plate K K'. Riveted to the under side of plate K is a plate, L, which is provided with an open slot, f, vertically through 40 its opposite end, that the plate may have a guide astride of a screw-bolt, M', put through the plate K', where the adjustment is made.

That the plate L may have a suitable lateral support, the plate K' is formed with side ears, 45 M M', and riveted to these ears at their under sides is a plate, N', which is countersunk on its top side to receive the said plate L.

The brackets D D are vertically slotted to receive the connected ends of forked springs 50 C C, whose free ends pass astride of lugs Q Q on the truck-disks I I'. Both parts of each

double spring, being sprung half of the thickness of the lugs outward, are in tension where the wheel-axles are at right angles to the center line of the boot-plate; consequently there 55 is no lost motion as there is where only one spring to a truck be employed. This is important, enabling the skater always to be sure of the position of the trucks. To insure strength with lightness of metal, the brackets 60 D D, by solid castings E, are connected with upper disks, H H, and brackets F F, the brackets being attached to the boot-plates by rivets in the ordinary manner.

The disk-plates H H I I are constructed on 65 the ordinary inclines outward and downward, to give a lateral incline to the boot-plate K K'; but the truck-frames I I' are so constructed that the axle-trees B B lie vertically under the center of motion of the disks H I, in contradistinction to the ordinary methods of placing the axle-trees on lines at right angles to the faces of the disks. By this means the trucks are farther apart, and in turning a corner the wheels are not brought so close to 75 the boot-plate, thereby contributing largely to the ease of motion and safety of the skates.

The disks H I are provided with a recess, a b, in which is placed an annular pivot-plate, c. The disks being in position, as shown at 80 Fig. 1, with the pivot between them, are held in position to turn by means of a screw, G, put through the disk I and pivot center-plate c, and tapped into the disk H, the head of the screw bearing against an ordinary washer, 85 J. This construction is such that the only function of the screw G is to hold the disks face to face, the wear coming on the pivot-plate c, which may be replaced where worn so as to give any lost motion. A stop, R, of 90 usual form, is employed to regulate the movement of the axle-trees.

It is proper to state that the skate shown is designed to supply the demand for perfection in action and elegance; but the truck attachments may be used in connection with wooden boot-supports, and serve a like purpose to that herein set forth.

Those portions shown but not described are well-known constructions, needing no explanation.

Having thus described my invention, I

claim and desire to secure by Letters Patent of the United States—

1. The disks H I, recessed out at *a b*, in combination with the annular pivot-plates *c*, and the screws *G*, for forming joint-connections for deflecting the wheels *A*, as specified.
2. The inclined brackets *F*, inclined disks *H I*, with the axle-trees *B*, placed in the truck-frames *I' I'* vertically under the center of motion of the disks *I I*, as specified.
3. In combination with inclined disks *H I* and lug *Q*, and the axle-trees *B B*, hung as specified, the double springs *C C*, to attain constant tension on the disks *I I*, as specified.

4. The brackets *D*, connecting plates *E*, and *F*, formed in single castings, in combination with springs *C C* and disks *H I*, as specified.

5. The adjustable boot-plate *K K'*, combined with the mortised plate *L*, countersunk 20 plate *M'*, ears *M*, screw-bolt *N'*, and nut *N*, as specified and shown.

BENNETT KINDBLADE.
